PYROXYLIN WAFER FOR ATTACHING HEELS
AND HEEL-BREAST FLAPS

Lewis J. Bazzoni, Swampscott, Mass., assignor to
United Shoe Machinery Corporation, Borough
of Flemington, N. J., a corporation of New
Jersey

Application October 12, 1937, Serial No. 168,599

2 Claims.

(Cl. 36—1)

This invention relates to the manufacture of shoes, and is illustrated as embodied in a pyroxylin wafer for use in attaching a Louis heel to a shoe and securing a covering flap split from the sole of the shoe to the breast of the heel.

It has been proposed to attach heels to shoes by the use of an activated pyroxylin wafer which is interposed between the heel and the heel seat of the shoe. It has also been proposed to interpose activated pyroxylin wafers between the breasts of attached Louis heels of shoes and heel-breast covering flaps split from the soles of the shoes preparatory to securing the flaps to the breasts of the heels by said wafers. The above practice, however, has not been adopted to any considerable extent, largely because of the difficulty experienced in handling the wafers, which are very flimsy after they have been activated. In order to insure that the flap be effectively secured to the shoe, it is desirable that the activated wafer register with the forward end of the split or crotch between the flap and the sole and also that the flap be smoothly arranged between the breast of the attached heel and the flap preparatory to applying the flap to the breast of the heel. It will therefore be appreciated that the effective interposing of the activated wafer between the flap and the breast of the attached heel is a slow and tedious operation.

It is an object of the present invention to provide a pyroxylin wafer by the use of which a heel may be attached to a shoe and a heel-breast-covering flap may be quickly and effectively secured to the breast of the heel. With the above object in view, and in accordance with a feature of this invention, there is provided a pyroxylin wafer comprising a rear portion adapted to be received in its entirety by the attaching face of the heel and a front portion of a size suitable to cover the breast of the heel, the wafer having a slot shaped to receive a tool for handling the wafer.

Preparatory to attaching the heel to the shoe and securing the flap to the breast of the heel the operator immerses the wafer in an activating fluid such, for example, as acetone, by the use of the tool a portion of which passes through the slot in the wafer, and positions said rear portion of the flimsy wafer upon the heel seat of the shoe by the use of the tool, while he holds said front portion of the wafer in an upstanding position away from the heel seat. The wafer is then forced into the crotch between the flap and the sole by the tool, and after the heel has been positioned upon the shoe it is forced against the

heel seat of the shoe under attaching pressure with said rear portion of the wafer interposed between the heel and the heel seat of the shoe, the flap then being secured by the upturned front portion of the wafer to the breast of the heel.

By providing the improved wafer the flap may be quickly and effectively secured to the heel during the heel-attaching operation thereby eliminating the above-mentioned slow and tedious operation of inserting a separate flimsy activated wafer between the attached heel and the breast flap preparatory to securing the flap to the heel breast. Moreover, by using the improved wafer an effective bond between the lip of the heel and the shoe is insured, since the wafer is wrapped around the lip as distinguished from a shoe in which the flap is secured by a separate wafer, which wafer is almost never effectively forced into the crotch between the flap and the sole.

The various features and advantages of the invention will be understood and appreciated from the following detailed description read in connection with the accompanying drawing, in which—

Fig. 1 is a plan view of a pyroxylin wafer which may be advantageously used for attaching a heel to a shoe and a heel-breast covering flap to the breast of the heel;

Fig. 2 is a perspective view of a hand tool shown supporting the pyroxylin wafer of Fig. 1 preparatory to activating the wafer;

Fig. 3 illustrates the wafer of Fig. 2 inserted in an activating fluid;

Fig. 4 is a perspective view showing the activated wafer being applied to the heel seat of the shoe and to the heel-breast covering flap by the use of the above tool, preparatory to attaching a heel to the shoe; and

Fig. 5 is a side view of portions of a machine by the use of which the heel may be attached to the shoe and the flap may be secured to the breast of the heel.

The invention is illustrated with reference to a shoe 20 (Figs. 4 and 5) the sole 22 of which has been split by the machine disclosed in United States Letters Patent No. 2,107,281, granted February 8, 1938, on an application filed in my name, to form a heel-breast covering flap 24. Said machine is provided with a rotary saw (not shown) which not only splits the sole 22 to form the flap 24 but also removes a layer of sole material to provide a heel-breast receiving shoulder 26 (Fig. 4) extending from one side of the sole to the other. After the heel-seat portion of the sole has been reduced to form a tab 28 and the sole has been positioned upon the shoe in the

manner disclosed in United States Letters Patent No. 2,125,328, granted August 2, 1938, on an application filed in my name, said sole is permanently secured to the shoe.

5 In accordance with the present invention, a heel 30 (Fig. 5) is attached to the shoe 20 and the flap 24 is secured to the breast of the heel through the use of a pyroxylin wafer 32, the rear portion 34 of which is similar to but slightly smaller than 10 the attaching face of the heel and the front portion 36 of which is large enough to cover the breast of the heel. The wafer is provided with a slot 38 shaped to receive the forward end of a slide 39 of a hand tool 40 through the use of which 15 the operator can effectively handle the wafer 32 while it is being activated and then apply the same to the shoe. The slot 38 (Fig. 1) which extends transversely of the wafer, is located between the front and rear portions 34, 36, respectively, of 20 the wafer, and is in alinement with a pair of laterally projecting shoulders 42 (Fig. 1) of said front portion. The rear end of the front portion 36 of the wafer may be considerably wider than an adjacent part of the rear portion 34 of the 25 wafer.

The hand tool 40 is provided with a U-shaped opening 44 for receiving the forward end of the slide 39. The slide 39 is guided for movement with relation to a plate 48 of the tool in directions indicated by arrows 50 through the provision of a pair of slots 52 which receive upstanding studs 54 secured to the plate. The slide 39 is also provided with a bent-up portion 56 which is normally engaged by the thumb of the right hand 30 of the operator and through which the slide may be conveniently moved forward to its operating position shown in Fig. 2 preparatory to picking up the wafer 32. When the rear ends of the slots 52 are in engagement with the studs 54 (Fig. 2), 35 the slide 39 is in its forward position and when the front ends of the slots are in engagement with the studs 54 the shoulder 58 of the slide is in alinement with the shoulders 60 of the plate 48.

After mounting the wafer 32 upon the tool 40 45 in the manner illustrated in Fig. 2, the operator immerses the wafer for a predetermined period in an activating fluid 62 (Fig. 3). When the operator has removed the wafer 32 from the activating fluid 62, he grasps the front end of the 50 wafer between the thumb and forefinger of his left hand, for example, and raises the front part 36 of the wafer until it is disposed at approximately right angles to the plate 48. The activated wafer 32 is then applied to the shoe, the 55 rear portion 34 of the wafer being positioned upon the heel seat of the shoe, and the front portion 36 of the wafer being arranged adjacent to the upturned flap 24, as illustrated in Fig. 4. When the operator has moved the shoulder 58 of the 60 slide into engagement with the central portion of the heel-breast receiving shoulder 26 he makes sure that the wafer has been positioned widthwise upon the heel seat of the shoe and then moves the plate 48 forward over the heel seat of 65 the shoe, causing the shoulders 60 of the plate to force the wafer into the crotch between the

flap 24 and the sole of the shoe. After positioning the heel 30 upon the shoe, the work is presented to a machine such, for example, as that disclosed in United States Letters Patent No. 2,123,926, granted July 19, 1938, on an application 5 filed in my name. Said machine comprises abutments 64 and 66 (Fig. 5) which are engaged by the tread and rear faces respectively of the heel, and a jack 68 which is raised to force the shoe with considerable pressure against the heel. 10 After the heel has been attached to the shoe the flap 24 is applied to the heel by the pad 70. Since the heel-attaching and flap-laying machine is fully disclosed in said United States Letters Patent No. 2,123,926, it will not be necessary 15 further to describe the same herein.

Although the invention has been described with reference to the shoe construction disclosed in said United States Letters Patent No. 2,125,328, 20 it will be understood that wafers similar to that illustrated herein may be used in connection with shoes the heel-breast covering flaps of which have been split forward of the heel-breast line of the sole of the shoe. In the illustrated construction the crotch between the flap 24 and the sole of 25 the shoe comprises the heel-breast receiving shoulder 26, but in a construction in which the flap is split by a knife forward of the heel-breast line of the shoe the angle formed by the base portion of the flap and the shank portion of the 30 sole of the shoe constitutes the crotch.

When the flap is split forward of the heel-breast line of the shoe the hand tool 40 is provided with shoulders 58, 60 of suitable height to insure that the activated wafer shall be effectively forced into the angle between the flap and the shank portion of the sole of the shoe. 35

If desirable, the rear portion 34 of the wafer 32 may extend only over the forward end of the heel-seat portion of the sole, in which case the heel may be secured to the shoe by other adhesives or by the commonly used temporary attaching screw.

Having described the invention, what I claim as new and desire to secure by Letters Patent of 45 the United States is:

1. A pyroxylin wafer for use in attaching a heel to a shoe and securing a covering flap to the breast of the heel comprising a rear portion slightly smaller than the attaching face of the 50 heel and a front portion of a size suitable to cover the breast of the heel, said wafer having an elongated slot which extends through and widthwise of the wafer and which is positioned between the front and rear portions of the wafer and is 55 adapted to receive a tool for facilitating the handling of the wafer.

2. A pyroxylin wafer for attaching a heel to a shoe and a covering flap to the breast of the heel comprising, a rear portion adapted to be received 60 in its entirety by the attaching face of the heel, and a front portion of a size suitable to cover the breast of the heel, said wafer having a slot shaped to receive a tool for handling the wafer.

LEWIS J. BAZZONI.
